EMERSON H. TOMPKINS, OF WATERBURY, CONNECTICUT, ASSIGNOR TO SCOVILL MANUFACTURING COMPANY, OF WATERBURY, CONNECTICUT, A CORPORATION OF CONNECTICUT

PENHOLDER

Application filed February 7, 1929. Serial No. 338,122.

This invention relates to certain improvements in pen-holders of that class in which there is provided a base and an open-ended holder for the pen.

5 In this class of pen holders it is desirable that the holder be so associated with the base that it can be moved to different positions, either up or down or sideways, relatively to the base.

10 It is further desirable in this class of holders that the holder and the base with which it is used be connected in a simple way so that the device may be economically produced.

15 It is the especial object of the present invention to provide improved constructions for securing the holders to the bases, so that the holders may have the desired movement relatively to the bases and which will at the same time securely hold the parts in place and be durable.

and be durable.
With these and other objects not specifically referred to in view, the invention consists in certain novel parts, arrangements and combinations which will be described in connection with the accompanying drawings and the novel features pointed out in the claims hereunto annexed.

Referring now to these drawings—

30 Fig. 1 is a top view of one form of holder. Figure 2 is a sectional view of the construction shown in Fig. 1, partly broken away.

35 Fig. 3 is a view of a spring used in assembling the parts.

Fig. 4 is a top plan view of another form of pen holder embodying the invention.

Fig. 5 is a sectional view of the holder shown in Fig. 4, partly broken away; and

40 Fig. 6 is a detail sectional view looking in the direction from the left hand side of Fig. 5.

Referring to said drawings, the invention
45 may embody holders of various forms, two
preferred forms of such holders being se-
lected to illustrate the invention.

Referring first to Figs. 1 to 3, there is provided a base 1, which may be of any suitable form, the base shown being square. This base may be of any suitable material. In

the particular construction shown, it is of a plastic composition 2 enclosed in a metal shell 3. This form of the invention includes a hollow pen holder 4, and means are provided for securing this holder to the base, so that the holder may stand in any desired position, two such positions being shown in Fig. 2. In the particular construction shown in this figure, there is provided a retainer 5 having a central opening 6 through which is inserted a ball 7 carrying a hollow plug 8 which is molded into the pen holder 4, the latter being of plastic material. Secured to the base is a retaining member 9 provided with an upwardly extending flange 10 forming an opening 11 for retaining a spring 12. This retaining member 9 is also provided with an outwardly extending flange 13 and the flange 10 of this member is externally threaded to receive a flange 14 on the part 5 before referred to.

This retainer 9 is secured to the base in any suitable manner, as being provided with a flange 15 which is closed in under the edges of an aperture formed in the metal shell 3 of the base, so that the retainer is held snugly in position. The spring may be of any suitable character, but, in the particular construction shown, comprises three legs 16 which terminate in a depressed seat 17 for receiving the ball. In assembling the parts, the spring retainer 9 is secured to the base, the spring then dropped into place in the opening 11, and the ball retainer 5 with the ball and pen holder then secured in place. It will be seen that the ball seats on the spring which acts to hold the pen holder in any position to which it may be moved.

Referring now to Figs. 4, 5 and 6, a somewhat modified form of holder is provided in which the holder may be maintained in any desired angular position relatively to the base. In the construction shown in these figures, instead of a ball for uniting the holder 4 to the base, there is provided a hollow plug or block 18 which is molded into the holder 4. This plug at one end is provided with an eye 19 which is secured by a screw 20 to a swivel member 21 having a split end, indicated at 22 in Fig. 6. This swivel member 100

has a flange 23 which seats on the spring 24 in the spring retainer 25, and is held in place by a retaining cap 26 having an inturned flange 27 which engages the lower end of the 5 swivel member holding the latter in place; the spring retainer 25 being secured to the base in a similar manner as retainer 9 here-
10 tofore referred to. It will be seen that with this construction the parts are securely held together, but the holder may be angularly adjusted as desired relatively to the base.

It will be seen that with the construction shown and described, simple and yet efficient and durable holders and associated parts 15 have been produced; the constructions comprising few members which are readily and quickly assembled. While the constructions shown and described have been selected as embodying the invention in its best forms, it 20 will be understood that the various changes and arrangements may be made in the specific construction and arrangement of the parts without departing from the invention as defined in the appended claims.

25 What is claimed is:

1. In an article of the class described, the combination of a pen holder, a plug to which the holder is molded, a base having a sheathing on its upper face, a spring holding block 30 fixedly secured to the base beneath the sheathing, and having a recess, a spring in the recess, a swivel connection between the plug and the spring, and a retainer for retaining the swivel in operative relation with 35 the block.

2. In an article of the class described, the combination with a pen holder, a plug to which the holder is secured, a base having a sheathing on its upper face, a spring holding 40 block having a recess, a spring in the recess, said block having a projecting portion held under the sheathing, a member carried by the plug and engaging the spring, and a retainer having telescopic relation with the 45 block for retaining the member in associated relation therewith.

3. A pen holder comprising a base of a plastic composition, a metal sheathing over the top of the base provided with an aperture, a supporting member having a projection closed in between the sheathing and the base and rigidly and fixedly held in position, and a pen holder resiliently supported by the supporting member.

5. In testimony whereof, I have hereunto set my hand.

EMERSON H. TOMPKINS.
